UNITED STATES PATENT OFFICE.

JESSE J. MOSS, OF TEMPLE, TEXAS.

SHOP-EASY SYSTEM.

Application filed May 14, 1927. Serial No. 191,442.

The present invention has reference to self-service stores and aims to provide a device of this character to be known as the shop easy system so constructed that the 5 purchasing of articles on the self-service plan will be greatly facilitated.

An important object of the invention is to provide carriers to receive the articles removed from the shelves by the purchasers, 10 the carriers being so constructed that they may be moved from place to place by the purchaser, thereby eliminating the necessity of the purchaser lifting and carrying baskets heavily laden with articles of merchandise.

A further object of the invention is to provide shelving arranged in circular formation and a plurality of arms pivotally supported centrally of the circle defined by the 20 arrangement of shelves so that when the arms are rotated the carriers at the ends thereof will move in proximity to the shelves, to the end that the purchaser may place the articles in the carriers with facility.

A still further object of the invention is to provide carriers mounted at the ends of the arms for swinging movement so that one carrier may be moved or swung inwardly 30 or outwardly to permit the same to pass another carrier.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 40 within the scope of what is claimed, without departing from the spirit of the invention.

Referring to the drawings:

Figure 1 is a plan view illustrating shelving and carriers constructed in accordance 45 with the invention.

Figure 2 is a sectional view through the shelving, and salesroom.

Figure 3 is an enlarged sectional view 50 taken on line 3—3 of Figure 2.

Figure 4 is a sectional view taken on line 4—4 of Figure 3.

Figure 5 is an enlarged sectional view 55 through one of the carriers and its supporting arm.

Figure 6 is an elevational view illustrating

the carrier support, the carrier being shown in section.

Referring to the drawings in detail, the reference character 5 designates the shelving which is circular in formation, the same embodying a plurality of superposed shelves 6 spaced throughout their lengths by means of the partitions 7 and defining compartments 8 in which the various articles for sale may be placed.

Supported centrally of the circle defined by the shelving, is a vertical hollow post 9 which has internal threads at its upper end for the reception of the threaded extremity 60 of the bearing member 10, the upper end of the hollow post providing a rest or support for the disks 11 which are superposed and provided with openings to receive the bearing member 10.

Bearings 12 are positioned between the disks to hold the disks in proper spaced relation with each other, the bearing members 12 being held against movement by the frictional contact of the disks at the end of 75 the bearing members 12.

The reference character 13 indicates the supporting arms which embody spaced members, the free ends thereof being formed into hooks 14 to receive the bails 15 of the carriers 16, to the end that the carriers may be readily and easily removed, or may be swung inwardly or outwardly out of the path of travel of the adjacent carrier permitting persons to pass while moving near the 85 shelves to remove articles therefrom.

Bearing members 17 are secured to the arms and fit over the tubular bearing members 12 to move freely thereover. Mounted 90 on each arm 13 is a plate 18 which is curved slightly to conform to the curvature of the supporting disk on which it is mounted, there being provided rollers 19 at the ends of the plate and adapted to rest on the disks to support the weight of the arms.

Cooperating with the rollers 19 is a roller 20 that extends from the rear end of each arm, the roller 20 being designed to engage the under surface of the adjacent upper disk to insure against binding of the rear end of the arm with which it is associated.

Thus it will be seen that due to this construction, a purchaser may take hold of one of the carriers and walk adjacent to the shelving removing packages therefrom, placing the packages in the carrier. At the rear 105 of the room defined by the circular shelving,

is a checker's desk 21, and it is contemplated in carrying out the system to have the checker examine the packages, place the amounts and cost thereon so that as the person moves 5 towards the exit indicated at A, the cashier seated at the desk 22 may add the amounts of the various packages and receive the pay therefor, thereby relieving congestion at the exit and at the checker's desk, by dividing 10 the responsibility of checking and receiving the pay for the articles between two persons.

In this way it will be obvious that the person making the purchases is relieved of the necessity of carrying heavily laden baskets 15 and may make the various purchases with facility.

While I have shown and described the arms as having hooks to accommodate the bails of the baskets or carriers, it is to be 20 understood that it is within the scope of the invention to provide the bails with hooks to be hooked over the arms.

I claim:

1. A self-service store system embodying 25 a salesroom, circular shelving arranged within the salesroom, supporting arms pivotally mounted centrally of the salesroom, the free ends of the arms moving adjacent to the shelving, carriers mounted to swing on the 30 free ends of the arms, and said arms adapted to be moved by persons making purchases.

2. A self-service store system embodying a salesroom, circular shelving arranged in the salesroom, a post supported centrally of the 35 salesroom, arms mounted on the post and adapted to swing in the arc of a circle, the free ends of the arms operating in proximity to the shelving, and removable swinging carriers mounted on the free ends of the arms.

3. A self-service store system embodying 40 shelving arranged in the form of a circle, a post supported centrally of the circle, arms radiating from the post and adapted to swing around the post, the free ends of the arms being disposed adjacent to the shelving, 45 and swinging carriers mounted on the free ends of the arms.

4. A self-service store system embodying 50 shelving arranged in the form of a circle, a post arranged centrally of the circle, a plurality of spaced superposed disks mounted at the upper end of the post, carrier arms supported by the post, wheels on the carrier arms and contacting with the disks to support the arms, and removable carriers mounted 55 at the outer ends of the arms and adapted to move in proximity to the shelving.

5. A self-service store system embodying 60 shelving arranged in the form of a circle, a post supported centrally of the circle formed by the shelving, arms supported by the post and adapted to rotate around the post, said arms having downwardly extended free ends, carriers, said carriers having bails, and hooks at the free ends of the arms to accommodate the bails.

6. A self-service store system embodying 65 shelving, a post supported adjacent to the shelving, arms mounted for rotation around the post, and supported by the post, carriers, means at the free ends of the arms for removably connecting the carriers to the arms, and said carriers adapted to swing on the arms.

In testimony that I claim the foregoing as 75 my own, I have hereto affixed my signature.

JESSE J. MOSS.
